ningen, Switzerland, a corporation of Switzer-
land

Application March 31, 1949, Serial No. 84,608

Claims priority, application Switzerland
December 20, 1948

23 Claims. (Cl. 112—158)

1

The present invention relates to a sewing machine comprising a shuttle located in the end of an arm and including a main shaft, driving an actuating mechanism for the needle-carrier in a to and fro vertical movement, a controlling device for the actuating mechanism of the feeding device for effecting modifications of the extent of the pitch of advancement of the cloth under the needle, and a mechanism causing displacements of the needle-carrier perpendicular to the advancement displacements of the feeding device.

The known machines enable generally to do straight or "zig-zag" seams by acting on a controlling element operable to put in service or out of service the device for the formation of the "zig-zag" stitch. The designers have further provided their machine with hand controlling elements operable to modify the size of the "zig-zag" stitch, that is to say to modify at will, either the extent of the lateral displacements of the needle-carrier, or the middle position of the needle-carrier, or the extent of the displacements of the feeding device and, consequently, the extent of the pitch of advancement of the cloth under the needle. These machines thus permit by acting on these controlling elements, the theoretical obtention of all kinds of "zig-zag" stitches. But it is clear that, practically, it is not possible to permanently manually operate these elements with all the desired accuracy for the obtention of a regular seam or decorative pattern.

The sewing machine in accordance with the invention, aims at remedying this drawback by the fact that it includes an operating station having two interchangeable cams driven in rotation by the main shaft, and of which the first one, mechanically connected to the needle-carrier, causes lateral displacements of the latter perpendicular to the advancement displacements of the feeding device, whilst the second one, mechanically connected to the driving mechanism of the said feeding device, causes modification of its advancement stroke.

The attached drawing shows diagrammatically and by way of example a form of construction of the sewing machine.

Fig. 1 is a profile view of the needle-carrying arm, certain parts being seen in axial cross-section, a part of the casing being broken away.

Fig. 2 is a profile view of the arm enclosing the driving mechanisms for the shuttle and the feeder.

Fig. 3 is a front view of the needle-carrying

2

arm and of the arm of the machine, certain parts of the casing being withdrawn.

Fig. 4 is a cross-section view along the line IV—IV of the Fig. 1 and on which only the manual controlling elements are illustrated.

Fig. 5 is a view from above of the needle-carrying arm, certain parts of the casing and of the elements of the operating station being broken away.

Fig. 6 is a part view of the needle-carrying arm, certain parts of the casing and of the operating station being broken away.

Figs. 7a to 7h illustrate a few types of simple "zig-zag" and decorative stitches which it is possible to obtain with the described sewing machine.

Fig. 8 is a perspective view of the driving devices for the feeding device and for the shuttle.

Fig. 9 is a part cross-section view of the small end of the connecting rod actuating the needle-carrier.

Fig. 10 is a top view of the driving mechanisms for the feeding device and for the shuttle housed in the arm.

Fig. 11 is a perspective detailed view of the actuating cams and a portion of the associated needle bar shifting mechanism.

Fig. 12 is a fragmentary elevational view of the needle bar shifting link partly in section as would appear on line XII—XII of Fig. 5.

Figs. 13a, 13b, 13c and 13d are similar plan views of four different cams usable in the apparatus of the present invention.

Fig. 14 is a fragmentary perspective view of a portion of the head of the sewing machine illustrating the cams in their positions.

Fig. 15 is a chart illustrating the various types of stitching obtained by placing the cams of Figs. 13a, 13b, 13c and 13d in the various positions of Fig. 14.

The machine shown by way of example on the attached drawing includes a column 1 bearing a work supporting arm 2 and a needle-carrying arm 3. All driving mechanisms for the various elements of the machine are contained in and

fixed to a frame constituting a casing of harmonious shape, formed by the arm 2, the column 1 and the needle-carrying arm 3. The upper arm or needle-carrying arm 3, contains a main shaft 4 carrying at one of its ends a fly-wheel 5 and a driving pulley 6. This upper arm 3 has at its free end a head containing the needle-carrier 7, the thread-puller (which is not shown) and their actuating mechanisms driven by the main shaft 4. These actuating mechanisms being not

the object of the present invention will not be described here in greater detail.

The column 1 contains transmission elements 8 connecting mechanically the main shaft 4 to the actuating mechanisms for the feeding device 10 and the shuttle 9, housed in the arm 2.

The machine, in accordance with the invention, includes at an operating station, actuating cams mechanically connected, on the one hand to the needle-carrier 7, and, on the other hand, to the actuating mechanism for the feeder. In the form of construction shown on the attached drawing, these cams are housed in the upper arm and includes an axle 11 (Fig. 1), revolving in a bearing 12 fastened to the frame or casing of the machine. This axle is driven in rotation by the main shaft 4 by means of a worm 13 and a gear 14 and carries, rigidly fastened on its end, a driving part 15. The latter has a seating surface 16, a cylindrical shank 17 and a threaded portion 18. Two actuating cams 19 and 20 kept at a distance one from the other by a stay 21 are engaged on the cylindrical shank and pressed on the annular seating face 16 by a tightening element 22 screwed to the threaded portion 18.

The angular positions of the cams 19 and 20, in relation to the axle 11, are defined by a finger 23 (Fig. 6) fastened to the driving part 15 and engaged in an opening 24 made in each of the said cams 19 and 20.

The cam 19 is mechanically connected (Figs. 3 and 5) to a support 25 rocking on an axle 26 and bearing the needle-carrier 7. This support 25 includes two guides 27 into which slides the rod 7 carrying the needle 28. The mechanical linkage between the support 25 and the cam 19 is achieved by means of an arm or link 29 hinged at r, by one of its ends, on the said support 25 and carrying at its other end a finger 30 kept into contact with a seating surface 32 by means of a spring 31 (Fig. 5). The position of this finger 30 along this seating surface 32 is defined by a controlling element R fastened to a socket 33 (Figs. 1, 5) revolving freely on an external cylindrical shank 34 of the bearing 12. This socket 33 carries an arm 35, of which one end is fitted with a finger 36 engaged in a groove made in the end of the arm 29. The seating surface 32 is fastened to a lever 37 hinged at 50 to the end of one of the arms of an operating lever 38 of which the second arm carries a small plate 39. The latter has a finger 40 engaged in a groove 41 in the form of a spiral made in a controlling element M revolving on an axle 43 fastened to the frame of the machine. This controlling element M is constituted by a knurled disc, of which a part of the periphery emerges from the casing of the machine through an opening 44. The angular position of the small plate 39 can be modified and fixed by means of an eccentric 45 fastened to the lever 38, engaged in a port 46, and to a securing element 47 constituted by a screw. The lever 38 is, in addition, subjected to the action of a spring 48 tending to cause its revolving in a clockwise direction around its pivot 49 fixed rigidly to the frame of the machine. Finally, the lever 37 further carries a finger 51 normally kept in contact with the profile of the cam 19 by the action of the spring 31.

The positions of the controlling element R are defined by a finger engaging itself, under the action of the self-elasticity of this element R, in drillings 52 made in a part 53 rigidly fixed to the frame of the machine.

The working of the actuating device for the

needle-carrier 7 in a rocking movement is as follows:

When the main shaft 4 is in rotation, it drives the cam 19, which in turn, actuates the finger 51, kept in contact with the profile of this cam 19. This finger 51 is therefore actuated in a to and fro movement against the action of the spring 31. Thus, the lever 37 performs a rocking movement around its axle 50 and actuates the support 25 in a similar movement by means of the arm 29 carrying the finger 30 kept in contact with the seating surface 32. The extent of the rocking movement of this support 25, as well as that of the needle-carrier 7, is a function of the position of the finger 30 along the seating surface 32. Indeed, the farther this finger 30 is from the pivot 50 of the lever 37 on the lever 38, the greater is the extent of the rocking movement of the needle-carrier 7.

The rocking of the support 25 effects displacements of the needle-carrier 7 in a way parallel to itself and perpendicular to the advancement displacement of the feeder. These displacements of the needle-carrier 7 are synchronized with the vertical reciprocating movement of the needle. The result is that the stitches are no longer in line one with the other, but in "zig-zag," as shown on the Fig. 7b or 7c, for instance. The position of the finger 30 along the seating surface 32 can be modified, chosen and fixed at will by acting on the controlling element R which makes it possible to choose and fix at will the extent of the displacement of the needle perpendicularly to the advancement displacement of the work feeder.

Practically, it is of advantage to design the profile of the cam 19 in such a way that the side displacements of the needle-carrier take place whilst the needle is outside the cloth, that is to say during the last part of the ascending stroke and the first part of the down stroke of the needle-carrier.

When the finger 30 is in front with the articulation 50 (position shown on the drawing Fig. 5), the extent of the rocking movement of the support 25 is naught. By further displacing by a step this element R in a clockwise direction from the position shown on the Fig. 5, the operator causes the finger 30 to pass to the side of the pivot 50 opposed to that carrying the finger 51. At this moment, the spring 31 causes the rocking of the lever 37 in a clockwise direction as far as a position defined by a stop n fastened to the lever 38, and for which the finger 51 is out of reach of the profile of the cam 19. For this last position of the controlling element R, the support 25 is consequently kept in a fixed position and the cam 19 can have no action at all on it, so that the machine does a perfectly straight seam.

The controlling element M enables the operator to choose and to fix the lateral position of the needle 28 in relation to the feeder. Indeed, the angular displacement of this controlling element M causes, by means of the finger 40 engaged in the groove 41 having a spiral form, an angular displacement of the lever 38 and therefore of the hinge 50 of the lever 37, and consequently, an angular displacement of the support 25 around its axle 26.

As shown on the drawing and in Patent No. 2,578,225 of December 11, 1951, the needle-carrier 7 is driven in its vertical reciprocating movement by a rod 54 hinged, on the one hand, on a crank pin 55 driven by the main shaft 4 and, on the other hand, by an axle 56 fastened to a collar 58 fixed on the needle-carrier 7. In order to

allow the displacements of the needle-carrier, parallelly to itself, this axle 56 slides freely in the drilling of the head of the rod 54 (Figs. 3 and 9). The latter has a groove 59, in which is engaged a guide 60 rigidly fixed to the frame of the machine.

The cam 20 is mechanically linked to the actuating mechanism of the feeder 10 (Figs. 2 and 8). This actuating mechanism will only be described here in so far as it is necessary for the good understanding of the working of the device causing modifications of the advancement stroke of the feeder 10. The latter is carried by a support 61 having the general form of a U, of which both wings have a guide 6 in which slides an axle 62, rigidly fixed to a collar 63. The latter is arranged at the end of an arm 65 pivoting on a vertical axle 64 carried, by its ends, by a part 66 in form of a fork, rigidly fixed to the frame of the machine. The arm 65 is rigidly fixed to one of the ends of an arm 67 by means of the axle 64 and of an adjusting and blocking screw 68. This arm 67 carries a rod 69 sliding in guides 70 and 71 and on the end of which is rigidly fixed an actuating element 72. The latter includes: a guiding rod 73 engaged in a port 80 made in the arm 67, a finger 74 engaged in a guide 75 having an adjustable position, and a seating element 76 kept in contact with the profile of an actuating cam 81 by the action of a spring 77 engaged on the rod 69 and resting on a seating surface 78 fastened to the arm 67 on the one hand and, on the other hand, on a seating stop 79 fastened to the rod 69.

The actuating cam 81, driven in rotation by transmission elements, periodically actuates the actuating element 72 against the action of the spring 77. Now, the finger 74 being engaged in the adjustable guide 75, it is clear that the actuating element 72 performs a to and fro movement in the plane of the guide 75 which is inclined in relation to the plane perpendicular to the rotation axle 82 of the actuating cam 81. Consequently, the arms 67 and 65 are driven by the rod 69 in a rocking movement around their pivoting axle 64. The result is that the feeder 10 is actuated in a to and fro movement parallel with the rotation axle 82 of the actuating cam 81.

The support 61 is, in addition, fixed to one of the ends of an elastic arm 83 articulated at 84 on the frame of the machine and of which the other end carries a rigid finger 84 kept, by the action of a spring 85, in contact with the profile of the cam 81. It follows that the feeder 10 is driven in a vertical to and fro movement perpendicular to the rotation axle 82 of the cam 81, which superimposes itself to the to and fro movement imparted by the actuating element 72 and the guide 75. While the extent of the displacements of the feeder in the vertical plane is of fixed and constant value, the extent of its displacement in the horizontal plane is a function of the angular position of the guide 75.

This guide 75 consists of a groove made in the front face of a part 86 (Fig. 2), including a hub 87, pivoting in a bearing 88, fastened to the frame the machine. This part 86 is rigidly fixed to the end of a driving shaft 89, housed in the column 1 and subjected to the action of a return spring 90.

The upper end of the driving shaft 89 (Fig. 1) carries an actuating element 91 provided with a flat surface 92 situated on a plane parallel with a diametrical plane of the driving shaft 89. This flat face 92 is kept in contact with a driving finger

93 by the action of the return spring 90. The finger 93 is rigidly fixed to the end of one of the arms of a lever 94, pivoted to an arm 96 by means of pin 97 revolving in a bearing 98, arranged in the arm 96. The second arm of the lever 94 (Fig. 6) carries a finger 99, kept in contact with the profile of the cam 20 of the operating station, by the action of the return spring 90. This is effected by bringing the end 109 of arm C in contact with finger 111 which holds the arm 96 fixed. The pin 97 carried by arm 96 is also stationary so that arm 94 can pivot about the pin 97. Spring 90 urges shaft 89 to rotate which causes the face 92 to move the finger 93 on the end of arm 94, which in turn urges the finger 99 of lever 94 against the surface of cam 20. The arm 96 is pivoted at 100 to the frame of the machine.

The operating station further includes a hand controlling element 102 operable to interrupt the mechanical connection linking the cam 20 to the guide 75. This controlling element consists of a three arm lever a, b, c (Fig. 4) and having a notch 103 engaged on a cylindrical extension 104 (Fig. 1) of a bearing carrying the main shaft 4 and rigidly fastened to the frame of the machine. The control element 102 is held on the said cylindrical extension by a blade spring 105 fixed by means of a screw 106 to the arm b. The arm a emerges from the casing of the machine through a port 107 (Fig. 5), arm b has a beak 108 which forms part of an arcuate camming surface adapted to engage the element 110 and thereby angularly displace the shaft 89. Arm c has a portion 109 bent at a right angle to the arm c and adapted to abut the member 111. The curved part of beak 108 of arm b and the beak 109 of arm c are intended to come into engagement alternately, in accordance with the angular position occupied by the arm a along the port 107, with actuating fingers 110 and 111, of which one is fastened to a collar rigidly fixed to the shaft 89, while the other constitutes an extension of the arm 96. Finally, the arm a is arranged between two adjustable stops 113 and 114 constituted each by a lever having a notch 115 engaged in a groove 116 made in the cylindrical shank 104, and provided with an actuating element 117 and a lock 118. This lock acts in conjunction with hollows 119 made in the part of the casing adjoining the port 107, under the action of a spring 120, resting, on the one hand, on the lever by its two ends, and, on the other hand, on the bottom of the groove 116 by its middle part.

The working of the device operable to modify the extent and the direction of the displacements of the feeder is as follows:

For all the angular positions of the controlling element 102 situated between the two stops 113, 114, placed in the angular positions shown on the Fig. 4, camming surface of arm b and of the beak 108 acts on the finger 110 and angularly displaces the driving shaft 89, and therefore the guide 75, to a given position, against the action of the spring 90. On the contrary, the beak 109 is out of reach from the finger 111, so that a spring 121 (Fig. 5) acting on the lever 94 keeps, on the one hand the finger 93 (Fig. 1) in contact with the face 92 of the actuating element 91 and, on the other hand, the finger 99 out of reach from the cam 20. Thus, for all these positions of the arm a of the controlling element 102, the mechanical connection between this cam 20 and the guide 75 is interrupted. The result is that the inclination of the guide 75, in relation to a plane perpendicular to the rotation axis of the cam 81

actuating the feeder element, is solely a function of the angular position of the arm *a* along the port 107 between the two adjustable stops 113, 114.

In addition, as shown on the drawing, Fig. 4, when the arm *a* is situated at an even distance from the stops 113 and 114, placed in the positions shown on the Fig. 4, the said arm *a* is then situated in front of a mark *o* (Fig. 5) and the groove 75 is situated in a plane perpendicular to the rotation axis of the cam 81. In consequence, for this position of the arm *a*, the lever 65—67 performs no rocking movement at all and the advancement stroke of the feeder is naught.

Finally, a study of Fig. 4 shows that by displacing the arm *a* in one direction or in another, the operator has the possibility:

(1) Of reversing the direction of the advancement stroke of the feeder and therefore the direction of the displacements of the cloth under the needle;

(2) Of modifying, choosing and fixing the extent of the advancement stroke of the feeder and therefore of choosing at will the extent of the advancement pitch of the cloth under the needle.

As the reversing of the direction of the advancement stroke is obtained by simply modifying the direction of inclination of the guide 75, this reversing can obviously be done during the running of the machine, which makes it possible to obtain a sequence of stitches such as shown on the Fig. 7a. In addition, the operator can fix in advance the values and the direction of the two respective advancement pitches by adjusting the position of the two adjustable stops 113 and 114, which greatly facilitates the accurate hand operation of the controlling element 102.

Now, if the operator puts in action the actuating device for the needle-carrier in a rocking movement, controlled by the cam 19, by operating the controlling element *R*, he can obtain very easily a sequence of "zig-zag" stitches, such as shown on Fig. 7b or Fig. 7c, for instance.

In order to get automatic modifications of the advancement pitch of the cloth while working, with a view of achieving a drawing or a decorative motive, it is sufficient to lower the arm *a* and the two stops 113 and 114 as far as into the end 125 of the port 107 (Fig. 4). For this latter position of the arm *a*, the beak 103 is out of reach from the finger 110 and the beak 109 acts on the finger 111 and keeps it in the position shown on the Fig. 6, against the action of the spring 121 on the one hand, and on the other hand, of the spring 90 of the axle 89. Thus, the finger 99 is kept in contact with the profile of the cam 20. The latter therefore actuates the lever 94, of which the finger 93 defines the angular position of the flat surface 92 fastened to the driving shaft 89 and provokes modifications in the inclination angle of the guide 75 and, in consequence, modifications of the extent and of the direction of the advancement displacements of the conveyer.

By examining the attached drawing, it will be seen that, according to the inclination direction of the guide 75 in relation to the plane perpendicular to the rotation axis of the actuating cam 81, the feeder 10 is actuated in the normal running direction or in the opposite direction. It is thus easily possible to achieve a seam forming drawings or decorative motives, such as shown on Figs. 7f and 7g, by properly choosing the cams 19 and 20 placed in the operating station.

Indeed, these cams are very easily interchangeable, since it is sufficient to lift a cover *C* and to unscrew the knurled nut 22 to permit their

withdrawning or placing. The diagrams of Figs. 7a to 7h show, by way of example, a few seam stitches which it is possible to obtain automatically and are sufficient to show the great possibilities given by the machine.

As shown in Fig. 15 it is possible to automatically produce sixteen different types of stitching with the machine according to the present invention.

10 The four lines of stitching shown in the upper horizontal row of the diagram of Fig. 15 is obtained by using only one of the four cams 1, 2, 3 and 4 shown in Figs. 13a, 13b, 13c and 13d respectively in the Z position indicated in Fig. 15. In each case represented in the upper horizontal row of Fig. 15 the feed is constant.

15 The second horizontal row of the diagram of Fig. 15 shows the types of stitching obtained with the same cams in the Z position, but also with certain cams in the T position.

20 The third horizontal row and the lower horizontal row show types of stitching obtained by various combinations of the cams 1, 2, 3 and 4 in the Z and T positions. Thus with four cams, it 25 is possible to obtain sixteen different types of stitching by arranging various combinations and permutations of the cams in the two positions on the cam shaft.

25 A form of construction has been described here 30 with reference to the attached diagrammatical drawing, but it is clear that all described elements and mechanisms can be simply replaced by their equivalents.

We claim:

35 1. A sewing machine including a main shaft, a needle-carrier, a driving mechanism driven by said main shaft and driving said needle-carrier in a vertical reciprocating movement, a feeder, an actuating mechanism driven by said main 40 shaft, a controlling device for said actuating device operable to effect modifications of the stroke of said feeder so as to permit modifications of the extent of the advancement pitch of the cloth under the needle, a mechanism 45 driven by said main shaft and effecting displacements of said needle-carrier perpendicular to the advancement displacements of said feeder, and comprising a cam-shaft driven by said main shaft, and two cams, the first controlling the 50 lateral displacements of the needle and the second the extent of the stroke of the feeder, said cams being removably mounted on said cam-shaft, said cams being independent one from the other, interchangeable and permutable, a 55 mechanical connection connecting the first of said cams to said needle-carrier and effecting lateral displacements of said latter perpendicular to the advancement displacements of said feeder, a first control element, means driven by said 60 first control element to interrupt the mechanical connection connecting said first cam to said needle-carrier, and a mechanical connection connecting the second of said cams to said actuating mechanism of said feeder and effecting modifications of the advancement stroke of said 65 feeder.

2. A sewing machine as claimed in claim 1 and comprising a first control device actuated by said first control element and operable to modify and fix the lateral extent of the displacements of said needle-carrier perpendicular to the advancement displacements of said feeder.

3. A sewing machine including a main shaft, a needle-carrier, a driving mechanism driven by said main shaft and driving said needle-carrier

in a vertical reciprocating movement, a feeder, an actuating mechanism driven by said main shaft, a controlling device for said actuating device operable to effect modifications of the stroke of said feeder so as to permit modifications of the extent of the advancement pitch of the cloth under the needle, a mechanism, driven by said main shaft and effecting displacements of said needle-carrier perpendicular to the advancement displacements of said feeder, and comprising a camshaft driven by said main shaft, and two cams, the first controlling the lateral displacements of the needle, and the second the extent of the stroke of the feeder, said cams being removably mounted on said camshaft, said cams being independent one from the other interchangeable and permutable, a mechanical connection connecting the first of said cams to said needle-carrier and effecting lateral displacements of said latter perpendicular to the advancement displacements of said feeder, a mechanical connection connecting the second of said cams to said actuating mechanism of said feeder and effecting modifications of the advancement stroke of said feeder, a second control element, and means driven by said second control element to interrupt said mechanical connection connecting said second cam to said actuating mechanism of said feeder.

4. A sewing machine as claimed in claim 3 and comprising a second control device actuated by said second control element and operable to modify and fix the extent and the direction of the advancement displacements of said feeder.

5. A sewing machine as claimed in claim 1 and comprising a first control device actuated by said first control element and operable to modify and fix the lateral extent of the displacements of said needle-carrier perpendicular to the advancement displacements of said feeder, an adjusting element and an adjusting device connecting said adjusting element to said needle-carrier and operable to modify and fix the lateral position of said needle-carrier.

6. A sewing machine as claimed in claim 3 and comprising a second control device actuated by said second control element and operable to modify and fix the extent and the direction of the advancement displacements of said feeder, and two adjustable stops disposed on one and the other side of said second control element, said control element being displaceable between said two adjustable stops.

7. A sewing machine as claimed in claim 1 and comprising a first control device actuated by said first control element and operable to modify and fix the lateral extent of the displacements of said needle-carrier perpendicular to the advancement displacements of said feeder, an adjusting element and an adjusting device connecting said adjusting element to said needle-carrier and operable to modify and fix the lateral position of said needle-carrier, an axle parallel with said needle-carrier, a support rocking on said axle, and guides in said rocking support, said needle-carrier sliding in said guides.

8. A sewing machine as claimed in claim 1 and comprising a first control device actuated by said first control element and operable to modify and fix the lateral extent of the displacements of said needle-carrier perpendicular to the advancement displacements of said feeder, an adjusting element and an adjusting device connecting said adjusting element to said needle-carrier and operable to modify and fix the lateral position of

said needle-carrier, an axle parallel with said needle-carrier, a support rocking on said axle, guides in said rocking support, said needle-carrier sliding in said guides, a finger, a spring 5 acting on said finger, a mechanical connection connecting said rocking support to said first control element, and a lever driven in a rocking movement by said first cam, said rocking lever having a seating surface thereon, said spring maintaining said finger in contact with said seating surface, whereby said rocking support is driven in a to and fro movement by said first cam.

9. A sewing machine as claimed in claim 1 and comprising a first control device actuated by 15 said first control element and operable to modify and fix the lateral extent of the displacements of said needle-carrier perpendicular to the advancement displacements of said feeder, an adjusting element and an adjusting device connecting said adjusting element to said needle-carrier and operable to modify and fix the lateral position of said needle-carrier, an axle parallel with said needle-carrier, a support rocking on said axle, guides in said rocking support, said 20 needle-carrier sliding in said guides, a finger, a spring acting on said finger and a mechanical connection connecting said rocking support to said first control element, a lever driven in a rocking movement by said first cam, said rocking lever having a seating surface thereon, said spring maintaining said finger in contact with said seating surface, whereby said rocking support is driven in a to and fro movement by said first cam, a hinge for said rocking lever, a prong 25 of said rocking lever cooperating with said first cam, and an extension of said seating surface extending on the side of said hinge opposed to that of said prong, whereby the push of said finger acting on said extension effects the disengagement of said prong with said first cam.

10. A sewing machine as claimed in claim 1 and comprising a first control device actuated by said first control element and operable to modify and fix the lateral extent of the displacements of said needle-carrier perpendicular to the advancement displacements of said feeder, an adjusting element and an adjusting device connecting said adjusting element to said needle-carrier and operable to modify and fix the lateral position of said needle-carrier, an axle parallel with said needle-carrier, a support rocking on said axle, guides in said rocking support, said needle-carrier sliding in said guides, a finger, a spring acting on said finger and a mechanical connection connecting said rocking support to said first control element, a lever driven in a rocking movement by said first cam, a seating surface on said rocking lever, said spring maintaining said finger in contact with said seating surface, whereby said rocking support is driven in a to and fro movement by said first cam, a hinge for said rocking lever, a prong of said rocking lever cooperating with said first cam, and an extension of said seating surface extending on the side of said hinge opposed to that of said prong, whereby the push of said finger acting on said extension effects the disengagement of said prong with said first cam, a fixed axle, a lever hinged on said axle, one arm of said lever bearing the hinge axle of said rocking lever, a finger carried by a second arm of said lever hinged on said fixed axle, said adjusting element having a groove in the form of a spiral, said finger being in engagement with said groove.

11. A sewing machine as claimed in claim 3

11

and comprising a second control device actuated by said second control element and operable to modify and fix the extent and the direction of the advancement displacements of said feeder, two adjustable stops disposed on one and the other side of said second control element, said control element being displaceable between said two adjustable stops, an adjustable guide controlled by said second cam or said second control element, and an actuating element of said actuating mechanism of said feeder, a part of said actuating element being in engagement with said adjustable guide.

12. A sewing machine as claimed in claim 3 and comprising a second control device actuated by said second control element and operable to modify and fix the extent and the direction of the advancement displacements of said feeder, two adjustable stops disposed on one and the other side of said second control element, said control element being displaceable between said two adjustable stops, a control shaft, an adjustable guide comprising a groove made in a part fastened to said control shaft, a seating element fastened to said control shaft, an actuating member driven by said second cam, a spring tending to keep said seating element in engagement with said actuating member, and an actuating element of said actuating mechanism of said feeder, a part of said actuating element being in engagement with said groove of said adjustable guide, whereby said second cam controls the advancement displacement of said feeder.

13. A sewing machine including a main shaft, a needle-carrier, a driving mechanism driven by said main shaft and driving said needle-carrier in a vertical reciprocating movement, a feeder, an actuating mechanism driven by said main shaft, a controlling device for said actuating device operable to effect modifications of the stroke of said feeder so as to permit modifications of the extent of the advancement pitch of the cloth under the needle, a mechanism driven by said main shaft and effecting displacements of said needle-carrier perpendicular to the advancement displacements of said feeder and comprising a camshaft driven by said main shaft, and two cams, the first controlling the lateral displacements of the needle and the second the extent of the stroke of the feeder, said cams being removably mounted on said camshaft, said cams being independent one from the other, interchangeable and permutable, a mechanical connection connecting the first of said cams to said needle-carrier and effecting lateral displacements of said latter perpendicular to the advancement displacements of said feeder, a mechanical connection connecting the second of said cams to said actuating mechanism of said feeder and effecting modifications of the advancement stroke of said feeder, a second control element and means driven by said second control element to interrupt said mechanical connection connecting said second cam to said actuating mechanism of said feeder and comprising a second control device actuated by said second control element and operable to modify and fix the extent and the direction of the advancement displacements of said feeder, two adjustable stops disposed on one and the other side of said second control element, said control element being displaceable between said two adjustable stops, a control shaft, an adjustable guide comprising a groove made in a part fastened to said control shaft, a seating element fastened to said control

12

shaft, an actuating member driven by said second cam, a spring tending to keep said seating element in engagement with said actuating member, an actuating element of said actuating mechanism of said feeder, a part of said actuating element being in engagement with said groove of said adjustable guide, whereby said second cam controls the advancement displacement of said feeder, a first seating element fastened to said control shaft and acting in conjunction with a first actuating member fastened to said second control element, a second seating element of said control shaft acting in conjunction with said second actuating member mechanically connected to a member acting in conjunction with the second of said cams.

14. A sewing machine as claimed in claim 13 in which said second control element includes three arms, the first one emerging from the 20 casing of the machine through a port, the second one carrying said first actuating member acting in conjunction with said first seating element of said control shaft for the manual operation of said latter, and the third one carrying a mobile 25 stop intended to act in conjunction with a third actuating member in order to establish a mechanical connection linking the second of said cams to said second seating element of said control shaft for the automatic operation of said latter.

15. A sewing machine as claimed in claim 13 in which said second control element includes three arms, the first one emerging from the 30 casing of the machine through a port, the second one carrying said first actuating member acting in conjunction with said first seating element of said control shaft for the manual operation of said latter, and the third one carrying a mobile 35 stop intended to act in conjunction with a third actuating member in order to establish a mechanical connection linking the second of said cams to said second seating element of said control shaft for the automatic operation of said latter, a lever having an arm cooperating with said second cam, and another arm carrying said second actuating member cooperating with said second seating element under the action of said 40 spring acting on said control shaft, said lever pivoting on an arm carrying said third actuating member and hinged on a fixed part, a spring acting on said lever and tending to keep it out of reach from the profile of said second cam.

16. A sewing machine as claimed in claim 3 and comprising a second control device actuated by said second control element and operable to modify and fix the extent and the direction of the advancement displacements of said feeder, two adjustable stops disposed on one and the other side of said second control element, said control element being displaceable between said 55 two adjustable stops, said adjustable stops consisting each of an arm having a notch engaged on a fixed cylindric portion and carrying said second control element, and a lock cooperating 60 under the action of a spring with openings made in the casing of the machine.

17. A sewing machine for zig-zag stitching including a main shaft, a needle-carrier, a driving mechanism driven by said main shaft and driving said needle-carrier in a vertical reciprocating movement, a feeder, an actuating mechanism driven by said main shaft, a controlling device for said actuating device operable to effect modifications of the stroke of said feeder so as to permit modifications of the extent of the

advancement pitch of the cloth under the needle, a mechanism driven by said main shaft and causing displacements of said needle-carrier perpendicular to the advancement displacements of said feeder and comprising a camshaft driven by said main shaft and having two similar cam receiving portions, and two cams independent one from the other, the first controlling the lateral displacements of the needle and the second the extent of the stroke of the feeder, identical means on each cam for removably mounting and fixing the same on either of the cam receiving portions of the cam shaft rendering the cams interchangeable and permutable, so that the one can be replaced by the other or both may be replaced by other cams.

18. A sewing machine including a main shaft, a needle-carrier, a driving mechanism driven by said main shaft and driving said needle carrier in a vertical reciprocating movement, a feeder, an actuating mechanism driven by said main shaft, a controlling device for said actuating device operable to effect modifications of the stroke of said feeder so as to permit modifications of the extent of the advancement pitch of the cloth under the needle, a mechanism driven by said main shaft and effecting displacements of said needle-carrier perpendicular to the advancement displacements of said feeder, and comprising a camshaft driven by said main shaft, and two cams, the first controlling the lateral displacements of the needle and the second the extent of the stroke of the feeder, said cam being removably mounted on said cam-shaft, said cams being independent one from the other, and interchangeable, a mechanical connection connecting the first of said cams to said needle-carrier and effecting lateral displacements of said latter perpendicular to the advancement displacements of said feeder, a first control element and means driven by said first control element to interrupt the mechanical connection connecting said first cam to said needle-carrier, a mechanical connection connecting the second of said cams to said actuating mechanism of said feeder and effecting modifications of the advancement stroke of said feeder, a second control element and means driven by said second control element to interrupt said mechanical connection connecting said second cam to said actuating mechanism of said feeder.

19. A sewing machine as claimed in claim 17, in which the two cams and all parts of the mechanism cooperating therewith are mounted in the casing of the machine.

20. A sewing machine for zig-zag stitching comprising means for imparting reciprocating movements to the needle, means including a single cam and a cam follower converting rotary motion into reciprocatory motion, a transmission mechanism for transmitting reciprocatory motion of the cam follower to the needle to effect transverse movements thereof and manually actuated means in said transmission mechanism operable for varying the ratio be-

tween the movements of said cam follower and the amplitude transverse movements of the needle, and operable for engaging and disengaging the cam follower with the cam.

21. A sewing machine according to claim 1 including also means enabling, during sewing, the amplitude and the direction of the feed movements of the feed-dog to be varied by means of a second manual controlling member, and mechanically by means of a mechanism capable of being engaged and disengaged at will for varying the character of the zig-zag stitching.

22. A sewing machine for zig-zag stitching comprising means for imparting reciprocating movements to the needle, means including a single cam and a cam follower converting rotary motion into reciprocatory motion, a link for imparting transverse movements to the needle, a pivoted lever carrying the cam follower and engaging one end of the link, and manually actuated means for shifting the position of engagement of the link and lever toward and away from one side of the pivot of the lever to vary the amplitude of the transverse movement of the needle and to the other side of the pivot of the lever to move the cam follower out of contact with the cam, said manually actuated means being also operable to shift the position of contact of the link and lever from said other side of the pivot wherein the cam follower is out of contact with the cam to the first mentioned side of the pivot to bring the cam follower into contact with the cam.

23. A sewing machine for zig-zag stitching comprising a feed dog, means for imparting feed movement to the feed dog, control means varying the amplitude and the direction of the feed movements of the feed-dog during sewing, means including a cam and cam follower for mechanically and automatically imparting movements to the control means to mechanically and automatically vary the amplitude and direction of the feed movements of the feed dog during sewing, a manually actuated member engageable

45 with the control means for actuating the control means to manually vary the amplitude and direction of the feed movements of the feed dog during sewing, means for applying and removing said cam follower to and from the cam, and means carried by the manually actuated member operable upon the manually actuated member engaging the control means to remove the cam follower from the cam and operable upon disengaging the manually actuated member from the control means for applying the cam follower to the cam.
